TEST TUBE HEATER

Cleophas E. Anderson and Darrle D. Moore, Dubuque, Iowa, assignors to Thermolyne Corporation, Dubuque, Iowa, a corporation of Illinois

Filed Feb. 13, 1964, Ser. No. 78,626

Term of patent 14 years

(Cl. D16—2)

FIG.1

FIG.2

FIG.3

FIG.4

FIG.5

FIG. 6

FIG. 1 is a perspective view of a test tube heater embodying our new design;

FIG. 2 is a top plan view of the test tube heater;

FIG. 3 is a side elevation view of the test tube heater;

FIG. 4 is an end elevation view, as seen from the left of FIG. 3, of the test tube heater design;

FIG. 5 is an end elevation view as seen from the right of FIG. 3; and

FIG. 6 is a bottom view, on a reduced scale, of the test tube heater design.

The dominant features of the design reside in the portions shown in full lines. The electrical cord member is fragmentarily shown in the drawings for convenience of illustration.

We claim:

The ornamental design for a test tube heater, substantially as shown and described.
